CLAIM

The ornamental design for a unitary portion control dispenser and spreader, as shown and described.

DESCRIPTION

FIG. 1 is a top perspective view of a unitary portion control dispenser and spreader incorporating the design invention;

FIG. 2 is a top plan view of the unitary portion control dispenser and spreader illustrated in FIG. 1;

FIG. 3 is a right side elevational view thereof;

FIG. 4 is a left side elevational view thereof; and,

FIG. 5 is a bottom plan view thereof.
